Y. TAJIMA.

WATER GAGE OR GAGE COCK.
APPLICATION FILED OCT 25, 1918.

1,373,274.

Patented Mar. 29, 1921.

Y. Tajima,
Inventor:

Geo. K. Kinnel
Attorney.

UNITED STATES PATENT OFFICE.

YOSHIIJU TAJIMA, OF OSAKAFU, JAPAN.

WATER-GAGE OR GAGE-COCK.

1,373,274.

Specification of Letters Patent. Patented Mar. 29, 1921.

Application filed October 25, 1918. Serial No. 259,702.

To all whom it may concern:

Be it known that I, YOSHIIJU TAJIMA, a subject of the Emperor of Japan, and resident of 286 Tennoji, Tennoji Mura, Higashinari Gun, OSAKAFU, the Empire of Japan, have invented certain new and useful Improvements in Water-Gages or Gage-Cocks, of which the following is a specification.

My present invention relates to a new and useful water gage or gage cock in which the body of a plug is made hollow, three holes or openings are bored around the outer surface of the said plug body with an interval of ninety degrees, respectively, a passage to communicate with the interior of a boiler by alining with any of the said three holes is specially provided at one side of the plug box, and a valve seat is provided in a valve chamber having a ball valve therein and arranged at that part of the plug projecting to the inside of the boiler.

An object of my present invention is to provide a water gage or gage cock which simplifies the process of cleaning the gage glass.

Another object of my invention is to provide a water gage which can be used effectively as test cock whenever needed in addition to its regular service.

A further object of my invention is to provide a water gage having a safety device so arranged and constructed that the ball valve arranged therein permits steam or hot water to pass freely under all conditions except the one case where the body of the water gage has been broken off by accident, when the said ball immediately stops the passage of the elements to insure absolute safety and effect economy.

A still further object of my invention is to provide a water gage cheaper in cost of manufacture than the water gage of my original invention for which I applied for patent the serial number of which being 241,031, filed June 20, 1918, by reducing volume and effecting a considerable saving in material or materials.

Other objects and advantages to be derived from the use of my present invention will be apparent from the following detailed description and the claims taken with an inspection of the accompanying drawings in which:

Figure 1 is a side elevational view of the invention as attached to the end plate of a

boiler, one of the two parts being cut vertically; Fig. 2 is a plan view of the same cut transversely; Fig. 3 is a front elevational view of the same, cut vertically; and, Fig. 4 is a magnified view of the safety device forming part of the invention.

Similar marks for reference designate like and corresponding parts throughout the several views.

Referring more particularly to the drawings, A is an end plate of a boiler; 1 is a plug box, which is screwed or bolted to the end plate; 2 is the body of a plug and is provided with a hollow space 3 therein; 4, 4', and 4'' represent, respectively, holes bored around the outer surface of the plug body; 5 is a gage glass; 5' is a blow-off opening; 6 is a passage to communicate with the interior of the boiler through the medium of any one of the three hole 4, 4', and 4''; 7 is a cleaning member rotatably provided to the inner end of the plug, by turning it with the plug the lime matter which clogs the passage of steam or hot water may be removed; 8 is an enlarged portion of the cleaning member and designed to serve as a seat for a ball valve 11; 9 is an extension of the plug located inside of the boiler; 10 is a valve chamber formed by the extensions 9 and 9'; 11 is a ball valve intended to automatically close the passage leading from the interior of the boiler to the inside of the plug, whenever required; and, 12 is a plug to prevent the ball valve from slipping out of the valve chamber, this plug being provided with an opening 13 to let steam or hot water pass therethrough.

As a first step, the plug boxes 1 and 1 are, respectively, screwed or bolted to the end plate A of a boiler and these are connected air-tight by means of a gage glass, and so far my present invention is similar to ordinary water gages hitherto in use. The differences between my invention and the said ordinary gages, that is, the features of my invention, lie in the fact that, through rotations of the plug body 2, the various connections of the passage 6 with the holes 4, 4', and 4'' bored around the outer surface of the hollow space 3 of the said plug body and the various positions of rotation of the upper plug relative to those of the lower plug make it possible in a certain case to ascertain the water level inside the boiler, to facilitate cleaning the gage glass in another

case by isolating or insulating it from the interior of the boiler, to let hot water jet out to the outside through the blow-off opening, and so on, and that the cleaning member 5 7 serves as the seat for the ball valve 11 to let steam or hot water pass freely on to the interior of the plug at normal times and even when the pressure inside the boiler is higher than that inside the plug, the said 10 ball valve completely closing or stopping the passage of steam or hot water only when the body of the cock is broken off by accident and the cleaning member is removed.

In short, the features of my present invention lie in the fact that it performs various functions through rotations of the plug body provided in each of the upper and lower plugs, and that through the unique 15 feature of the cleaning member the use of the ball valve has been considerably extended, though the ball valve itself has been in existence.

To describe more fully about directions of rotations of the upper and lower plug 20 bodies and their functions:

When both the upper plug body and the lower one are rotated to the position as 25 shown in Fig. 1, steam or hot water will enter the hole 4 through the passage 6, pass through 4' and 4'', and escape through the opening 5'; when the upper plug body and the lower one are placed in a corresponding 30 position by rotating them by ninety degrees, the gage glass will communicate with both the steam and hot water inside the boiler through the upper and lower plug boxes and the pressure will be uniform throughout 35 the whole apparatus, so that the water level inside the boiler will be precisely ascertained by referring to the height of water 40 inside the water gage; and, when the upper plug box and the lower one are rotated another ninety degrees, the gage glass will be utterly isolated or insulated from the inside 45 of the boiler, and then it is possible to clean the gage glass thoroughly.

My present invention is an improvement 50 on my original invention, referred to hereinbefore, and by comparing these two water gages, it will be readily seen that in the original one an opening and closing pipe, 55 communicating with the outer circumference of the plug body alone, was specially provided which necessarily caused its volume to be bulky; whereas, in the present invention, a passage is provided at one side of the plug box, in place of the opening and closing pipe, to connect the hollow space inside the plug body with the interior of a 60 boiler and three holes are provided around the surface of the plug body to conform with the said passage, to enable the present invention to perform all the functions that 65 the original one possesses, with the consequence that its volume has been consider-

ably reduced and remarkable saving in material has been effected in the present invention.

Having thus fully described my invention, what I claim as new and desire to secure by Letters Patent is:

1. In a water gage, a body having an internal chamber and opposed ports communicating with the chamber, said body also having an inlet passage communicating at 75 one terminal with the chamber in the plane of the opposed ports, and a plug rotatably mounted in the ported portion of the body having an internal chamber and a plurality of ports communicating therewith adapted to be moved into registration with the ports and passage of the body whereby to establish communication between the two opposed ports with or without connection with the passage, or connect the passage with 80 both of the opposed ports or either of said ports separately.

2. In a water gage, a body having an internal chamber and opposed ports communicating therewith, said body also having a passage communicating at one terminal with the chamber in the plane of the opposed ports and communicating at its opposite terminal with said chamber at a point remote from the opposed ports, and a rotary 95 plug mounted in the ported portion of the body having an internal chamber and a plurality of ports communicating therewith adapted to be selectively registered with the ports and passage of the body 100 whereby to establish communication between the two opposed ports with or without connection with the passage or to connect the passage with both of the opposed ports or either of said ports separately.

3. In a water gage, a body having an internal chamber and opposed ports communicating with the chamber, said body also having a passage communicating at one terminal with the chamber in the plane of the opposed ports and communicating at its opposite terminal with the chamber at a point remote from said ports, a valve seat in said chamber intermediate the terminals of the passage, a valve associated with said seat, 110 and a plug rotatably mounted in the ported portion of the body having an internal chamber and a plurality of ports adapted for registration with the ports and passage of the body whereby to establish communication between the two opposed ports with or without communication with the passage or to establish communication between the passage and both of the opposed ports or either of said ports separately.

4. In combination, a body provided with a longitudinal opening and having a port therein adapted to receive a gage tube, said body also having a passage communicating at one terminal in the plane of said port, 130

a ported plug adapted to establish communication between the terminal of the passage and the port of the body, said plug being removable through one end of the body,
5 an internal valve seat adjacent the opposite terminal of the body, a valve adapted to engage said seat to prevent passage of fluid through said body, and means carried by said plug normally retaining the valve in
10 open position.

5. In a water gage, a body having an internal chamber and a passage communicating at one terminal with the chamber, said body having a port disposed in the plane of
15 one terminal of the passage, a gage tube engaged with the port, a ported plug rotat-

ably mounted in one terminal of the body controlling communication between the terminal of the passage and the port in the body, the portion of said body at the terminal opposite the plug being internally restricted to provide a valve seat, a valve engageable with said seat and normally retained in open position by engagement of a portion of said plug therewith, and means 20 carried by said plug adapted to remove accumulations from the wall of the restricted portion of the chamber of the body during removal of the plug.

In testimony whereof I affix my signature 25
hereto.

YOSHIUJI TAJIMA. [L.S.]
